(57) **CLAIM**

The ornamental design for a brush with handle, as shown and described.

DESCRIPTION

FIG. 1 is an elevation view of the brush with handle.

FIG. 2 is an elevation view of the other side of the brush with handle, rotated 180° from the view of FIG. 1.

FIG. 3 is an elevation view of the brush with handle, rotated 90° from the view of FIG. 2.

FIG. 4 is an elevation view of the brush with handle, rotated 180° from the view of FIG. 3.

FIG. 5 is an end view of the brush with handle; and,

FIG. 6 is a view of the other end of the brush with handle.
The broken line outline representing bristles, is for illustrative purposes only and forms no part of the claimed design.
